UNITED STATES PATENT OFFICE.

ANNA LOUISE SKILLMAN, OF PLUCKEMIN, NEW JERSEY.

PAPER-CLIP.

1,270,451.

Specification of Letters Patent. Patented June 25, 1918.

Application filed December 18, 1915. Serial No. 67,542.

To all whom it may concern:

Be it known that I, ANNA L. SKILLMAN, a citizen of the United States, residing at Pluckemin, in the county of Somerset, State 5 of New Jersey, have invented certain new and useful Improvements in Paper-Clips; and I do hereby declare the following to be a full, clear, and exact description of the invention, such as will enable others skilled in 10 the art to which it appertains to make and use the same.

This invention relates to improvements in paper fasteners.

The principal object of the invention is to 15 provide a paper fastener or clip which is simple and cheap in construction and which is effective in operation.

Another object is to provide a device of this character which is not only useful as 20 a means of holding a number of papers together but will be ornamental, as well.

Other objects and advantages will be apparent from the following description when taken in connection with the accompanying 25 drawing.

In the drawing:

Figure 1 is an elevation of my improved paper fastener in operative position;

Fig. 2 is a vertical section on the line 2—2 30 of Fig. 1; and

Fig. 3 is a perspective view of the fastener.

Referring particularly to the accompanying drawing, the paper clip is formed of a single piece of flat metal 10, cut into the form 35 of a horseshoe, as shown. This strip of metal is cut intermediate its edges on a line extending from the point 11, which is adjacent one of the ends of the metal, to a point

12, adjacent the other end. Thus there are formed two concentrically arranged and 40 curved or bowed portions adapted to be slightly separated to receive the edges of a number of papers therebetween to be held thereby. The metal may be of any desired size or thickness, but when the same is made 45 of metal it is preferable that it be resilient to permit of the parts springing back into normal flat position after having been removed from the papers. This resiliency will also serve to urge the bowed portions 50 clampingly against the papers.

If desired, the device may be made of celluloid with colored designs or suitable wording, such as "Mottoes", so that the device can be used as a book-mark. In this use of 55 the device it would be preferable to make the device considerably longer than when it is used as an ordinary paper clip, thus permitting the device to be inserted a considerable distance within the book. 60

What is claimed is:

A paper clip, comprising a horse-shoe shaped blank terminating in a pair of freely extending spaced fingers, said blank having an arcuate slot subdividing its body into two 65 concentric arcuate sections bendable at their bases and on the long axis of the blank, said slot terminating short of the bases of said fingers at such a suitable distance only as to preserve the unity of the blank. 70

In testimony whereof, I affix my signature, in the presence of two witnesses.

ANNA LOUISE SKILLMAN.

Witnesses:

SAMUEL P. SUTPHEN,
LILLIAN S. KOEHLER.
